METHOD FOR PRESSING GARMENTS
George Schlemon, 3060 Pharr Court NW, Atlanta, Ga.
Filed Feb. 4, 1963, Ser. No. 259,769
5 Claims. (Cl. 38—15)

This invention relates to a method for pressing garments and more particularly to a method for pressing garments which does not result in the excessive pressure and heat that tend to shine garments and damage synthetic fabrics and blends, and which for this and other reasons results in the improved pressing of garments and permits the use of an improved, inexpensive upper buck needing only relatively light structure to support and to raise and lower it.

Previously known methods for the commercial pressing of garments have employed presses having a pad covered lower buck, and an upper buck which is raised and lowered to engage a garment placed on the lower buck. The upper buck has generally an upper chamber in which steam under pressure is stored and a lower chamber into which steam from the upper chamber is released for application through a plurality of holes.

The storing of steam in the upper buck and the repeated release of steam into and out of the upper buck causes the upper buck to become quite hot. This causes a garment being pressed to be exposed not only to the heat of the steam, but also to the heat of the upper buck. It is the resulting excessive heat applied to the garment which with excessive pressure puts a shine on garments being pressed. It is this excessive heat which damages synthetic fabrics and blends and other heat sensitive materials. Moreover, because of the storing of high pressure steam and of the need to exert heavy pressure, upper bucks have been massive and have required large and expensive structure to support, raise and lower them.

Since steam is applied from the upper buck to the garment backed by the pad on the lower buck and before a drying vacuum is applied, previously existing methods for pressing garments have also resulted in excess steam being spread about the area of the press when the upper buck is lowered and pressed against the garment and the lower buck. Both this excess steam and the excessive heat of the exposed upper buck structure serve to make existing presses and methods of pressing garments hazardous to the operator of the press. This fact, and the massive structure of the upper buck necessary to hold and release steam and to exert large pressing pressures account for the failure of previously existing commercial methods and presses for pressing garments to be suitable for home use. The apparatus required has been too large, expensive, and hazardous for such use.

This invention completely eliminates these difficulties and limitations of previously existing methods for pressing garments. The method of the invention eliminates the massive, steam containing upper buck with its hazards to the operator and its excessive heat and pressure which damage synthetic fabrics and blends and which put a shine on other materials. It permits an improved upper buck of light and inexpensive construction which, although suitable for use with previously existing pressing methods, is particularly suited to the method of the invention.

These and other improvements are achieved because steam is introduced through the lower buck and diffused through the pad on the lower buck and into the garment while a vacuum on the upper buck draws the steam through the garment and out of the press where it can be exhausted or recirculated to the lower buck. The upper buck contains no stored steam and because the lower buck is covered with a pad, neither the up-

2

per buck nor the lower buck will damage or shine materials or be a hazard to the operator.

Moreover, since the steam being introduced through the lower buck is completely contained within the press as it passes through the pad covered lower buck, the garment and the upper buck, there is no excess steam spreading about the area of the press to cause heat and make the operator uncomfortable or to present a hazard to the operator. Thus, the method of the invention described herein permits existing presses or improved presses specifically adapted to its use to effectively press garments without danger of damaging or shining the garment and to be comfortably and safely used by the operator. Improved presses specifically adapted to the method of the invention are of lighter and less expensive construction as well as completely safe and comfortable to use, and the home pressing of garments to commercial standards is entirely practical.

These and other features and advantages of the invention will be more clearly understood from the following detailed description and the accompanying drawing, in which FIG. 1 is a side elevational view of a press suitable to the method of the invention and showing the improved upper buck and the lower buck in section.

This drawing and the following detailed description disclose a preferred specific embodiment of the invention, but neither the method nor the apparatus of the invention are limited to the details disclosed since they may be embodied in other equivalent forms.

This invention is most easily understood by considering the sequence of steps used to press a garment. The garment is first placed on the pad 10 of the lower buck 11. The pad 10 is of known type having the usual porous and resilient layer of material 22 and the pressing surface 12 of the upper buck 13 is brought into contact with the garment with light pressure so as to only lightly hold the garment between the upper buck 13 and lower buck 11 and prevent creeping of the garment on the pad 10 of the lower buck 11.

Steam under seventy to eighty pounds pressure is then introduced into the chamber 14 of the lower buck 11 through an intake pipe 15. Steam under this pressure has been found to have adequate moisture content for the method of the invention. The steam diffuses throughout the chamber 14 and passes upward through a plurality of holes 16 in the upper plate 17 of the lower buck 11, through the pad 10 and into the garment being pressed. A vacuum is applied to exit pipe 18 and the chamber 19 of the upper buck 13 simultaneously with or shortly after the introduction of steam into the chamber 14 of the lower buck 11, and the steam entering the garment being pressed from the chamber 14 of the lower buck 11 is drawn through the garment and into the chamber 19 of the upper buck 13 and the exit pipe 18 through which it passes, to be exhausted or trapped for recirculation to the lower buck.

The application of a vacuum to the chamber 19 of the upper buck 13 while steam is being applied to the garment from the chamber 14 of the lower buck 11, insures that the work area of the press operator adjacent the press will not become warm and uncomfortable or hazardous because of the presence of excess steam. The steam is contained by the pad 10 and the garment until it passes through the garment and is immediately drawn into the upper buck 13 after passing through the garment. Moreover, the application of the vacuum while steam is being applied to the garment also prevents excess moisture from collecting in the material of the garment. This improves the quality of pressing and makes drying the garment less difficult.

Subjecting pipe 18 and chamber 19 to a vacuum can

be accomplished in any conventional manner as shown in the drawing and exemplified by the various plumbing arrangements shown in the United States Patents No. 1,326,982 to Spencer; 1,501,685 to Parker; and 2,784,509 to Ketchum, et al.

Drying is accomplished by continuing the vacuum being applied to the chamber 19 of the upper buck 13 after the introduction of steam into chamber 14 of the lower buck 11 has been discontinued. This continuing vacuum quickly dries the garment by withdrawing all moisture from the garment by the flow of dry air through the lower buck. The dry air is obtained by providing the intake pipe 15 with a valve 21 of known type which permits either steam or dry air from the atmosphere or other suitable source to be introduced into chamber 14. The continuing vacuum, by itself and in combination with the application of a vacuum during the introduction of steam, has the further advantage of keeping the lower buck 11, the pad 10 and the upper buck 13 free from moisture.

The vacuum further tends to draw off the heat generated by the steam and therefore tends to maintain the device at a cooler temperature as compared to a device operating with the same steam temperature and having no similar air circulation therethrough. This helps to prevent heat damage to the garments and allows the operator to operate the device in a safe and comfortable atmosphere.

The fact that steam is not stored in the upper buck 13 and passes through the upper buck 13 only after it has lost some of its heat while passing through the pad 10 and the garment, prevents the upper buck 13 from being hot from the presence of steam. This, and the elimination of heat causing excess moisture by the vacuum as described above, insure that the upper buck 13 will not become so hot as to shine the garment or damage synthetic fabrics or blends. As a matter of fact, the lack of upper buck 13 heat will prevent a shine on garments even when substantial mechanical pressure is applied to the garment by the upper buck 13. Moreover, since the steam-containing lower buck 11 is covered by a pad 10, the lack of the excessive heat usually associated with the upper buck 13 also insures that there are no exposed metal surfaces to injure the operator.

The method of the invention is particularly suited to the automatic sequencing and timing of operations since all pressing operations occur after the upper buck 13 is lowered and before it is raised. The sequencing of the operations and the operations themselves can be accomplished by known apparatus. Even previously existing presses may be used with appropriate changes in the manner in which steam and vacuum are applied. However, with presses constructed with the method of the invention in view, the method possesses the additional advantage of permitting the upper buck 13 to be of light construction.

This is because the upper buck 13 exerts only light pressure and does not contain steam under pressure. Not only may the upper buck 13 be less expensive, but the structure used to support and to raise and lower it may be less massive and expensive. The result is a press suitable for home as well as commercial use because it is relatively inexpensive and less massive than previously existing presses, and because it avoids the escaping excess steam and the hot metal surfaces associated with previously existing methods for pressing clothes.

Preferably, the improved press has an upper buck 13 with a single chamber 19, a pressing surface 12 constructed entirely of wire mesh 20, and means of known type for applying a vacuum through exit pipe 18 to the chamber 19. The wire mesh 20 is closely spaced mesh of known type having a rough textured surface. The wire mesh 20 may be one or a plurality of layers thick. However, it has been found that three layers of wire mesh 20 provide a pressing surface 12 with sufficient strength to not only hold a garment and prevent creeping, but also to exert adequate and substantial pressing pressure

where such pressure is required by the material of the garment.

Whether used with the method of the invention or previously existing pressing methods, the rough texture of the wire mesh 20 and the fact that the wire mesh 20 does not readily retain heat help to prevent the crushing of material and the heat which shines garments when combined with either light or heavy mechanical pressure on the garments. Moreover, because each strand of wire mesh 20 is of small diameter, a pressing surface 12 of wire mesh 20 does not have any relatively large flat portions to collect moisture or to mark the garment when the pressing surface 12 is in contact with the garment. Used with the method of the invention, the porous structure of the wire mesh 20 of the pressing surface 12 also enhances the upward flow of steam and dry air under the influence of the vacuum applied to the chamber 19 of the upper buck 13.

It will be obvious to those skilled in the art that many variations may be made in the embodiments here chosen for the purpose of illustrating the present invention without departing from the scope thereof as defined by the appended claims.

What is claimed as invention is:

1. A method for pressing a garment with a garment press having an upper buck and a lower buck, said method comprising, in combination, the steps of firstly placing the garment in pressing position on the lower buck, secondly exerting light mechanical pressure on the garment with the upper buck, thirdly passing steam into the garment through the lower buck only while simultaneously applying a vacuum to the garment through the upper buck, fourthly discontinuing the passage of steam into the garment through the lower buck while continuing the application of a vacuum to the garment through the upper buck, fifthly while passing dry air into the garment through the lower buck, sixthly discontinuing the application of a vacuum to the garment through the upper buck and the passage of dry air into the garment through the lower buck, seventhly discontinuing the light mechanical pressure exerted on the garment by the upper buck, and finally removing the garment from the lower buck.

2. A method for pressing a garment with a garment press having an upper buck and a lower buck, said method comprising, in sequence, the steps of exerting light mechanical pressure on the garment with the upper buck, passing steam into the garment through the lower buck only while simultaneously applying a vacuum to the garment through the upper buck, discontinuing the passage of steam into the garment through the lower buck while continuing the application of a vacuum to the garment through the upper buck, passing dry air into the garment through the lower buck, discontinuing the application of a vacuum to the garment through the upper buck and the passage of dry air into the garment through the lower buck, discontinuing the light mechanical pressure exerted on the garment by the upper buck.

3. A method for pressing a garment with a garment press having an upper buck and a lower buck, said method comprising, in combination, the steps of firstly passing steam into the garment through the lower buck only while applying a vacuum to the garment through the upper buck, secondly discontinuing the passage of steam into the garment through the lower buck while continuing the application of a vacuum to the garment through the upper buck, thirdly passing dry air into the garment through the lower buck, and finally discontinuing the application of a vacuum to the garment through the upper buck and the passage of dry air into the garment through the lower buck.

4. In a method for pressing a garment between an upper buck and a lower buck, the steps of firstly passing steam into the garment through the lower buck only while simultaneously applying a vacuum to the garment through the upper buck, and secondly discontinuing the passage of

steam into the garment through the lower buck while continuing the application of a vacuum to the garment through the upper buck.

5. In a method for pressing a garment positioned on a lower buck, the steps of in sequence exerting light pressure on the garment with an upper buck, drawing steam through the garment from the lower buck only with a vacuum applied through the upper buck, and drawing dry air through the garment with the said vacuum after the drawing of steam through the garment has been discontinued.
